MAKE-UP TRAY

Clifford J. Francois, Jr., New Orleans, La.

Application August 28, 1950, Serial No. 11,970

Term of patent 7 years

(Cl. D86—1)

To all whom it may concern:

Be it known that I, Clifford J. Francois, Jr., a citizen of the United States residing at New Orleans, in the Parish of Orleans, State of Louisiana, have invented a new, original, and ornamental Design for a Make-Up Tray, of which the following is a specification, reference being had to the accompanying drawing, forming a part hereof.

I claim:

The ornamental design for a make-up tray, as shown,

CLIFFORD J. FRANCOIS, JR.
